Primary Examiner — Jeffrey D Asch*Assistant Examiner* — Natasha Vujcic(74) *Attorney, Agent, or Firm* — Grandview Law PLLC; Brian L. Johnson(57) **CLAIM**

The ornamental design for a holder for washing diapers or other materials, as shown and described.

DESCRIPTION

FIG. 1 is a first front isometric view of a first embodiment thereof.

FIG. 2 is a second front isometric view thereof.

FIG. 3 is a rear isometric view thereof.

FIG. 4 is a first front isometric view of a second embodiment thereof.

FIG. 5 is a second front isometric view thereof.

FIG. 6 is a rear isometric view thereof.

FIG. 7 is a first front isometric view of a third embodiment thereof.

FIG. 8 is a second front isometric view thereof.

FIG. 9 is a rear isometric view thereof.

FIG. 10 is a first front isometric view of a fourth embodiment thereof.

FIG. 11 is a second front isometric view thereof; and,

FIG. 12 is a rear isometric view thereof.

The broken lines shown in the drawings that are immediately adjacent to the shaded areas, and define an unshaded regions, represent the bounds of the claim, while the broken lines within the boundaries are directed to environment. The broken lines and the unshaded regions form no part of the claimed design.
